(57) **CLAIM**

The ornamental design for a tub and shower enclosure, as shown and described.

DESCRIPTION

In a preferred embodiment, the nature of this product is a tub and shower enclosure primarily useful for washing humans.

FIG. 1 is a top, left, front perspective view of a tub and shower enclosure according to my new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a rear elevational view thereof; and,

FIG. 8 is a top, right, front perspective view of a tub and shower enclosure, the front elevational, left side elevational, right side elevational, top plan, bottom plan and rear elevational views thereof are mirror images of respective FIGS. 2-7.

The broken line representations in the figures are for the purpose of illustration only, and form no part of the claimed design.
